United States Patent Office

Des. 185,162
Patented May 12, 1959

185,162

FOUNTAINHEAD

John A. Metzger, Chicago, Ill., assignor to Stanley Knight Corporation, Chicago, Ill., a corporation of Illinois

Application February 21, 1958, Serial No. 49,749

Term of patent 14 years

(Cl. D2—3)

The rear of the article is plain.

I claim:

The ornamental design for a fountainhead, as shown and described.
